UNITED STATES PATENT OFFICE.

FREDERICK PEARCE, OF NEW YORK, N. Y., ASSIGNOR TO W. B. STERRETT,
OF SAME PLACE.

RAILWAY-SIGNAL.

SPECIFICATION forming part of Letters Patent No. 372,865, dated November 8, 1887.

Application filed February 26, 1887. Serial No. 228,955. (No model.)

To all whom it may concern:

Be it known that I, FREDERICK PEARCE, of the city, county, and State of New York, have invented a new and Improved Railway-Signal, 5 of which the following is a specification, reference being had to the annexed drawings, forming a part thereof, in which—

Figure 1 is a diagram showing my improved signal system arranged for open circuit. Fig. 10 2 is a diagram showing my improved signal system arranged for closed circuit. Fig. 3 is a plan view of the track-instrument. Fig. 4 is a transverse section taken on line $x-x$ in Fig. 3. Fig. 5 is an enlarged detail plan view of the circuit opener and closer with the cover removed. Fig. 6 is a longitudinal section. Fig. 7 is a transverse section of the switch-casing, taken on line $x'-x'$ in Fig. 5, and Fig. 8 is a transverse section taken on line $y-y$ in Fig. 5.

20 Similar letters of reference indicate corresponding parts in all the views.

My invention consists in a novel arrangement of circuits, track-instruments, and relays, in connection with electro-magnetic signaling-lanterns arranged to be operated either in 25 open or closed circuit system by the action of a passing train, so as to display a danger-signal during the passage of the train over the section of the track protected by the signal.

30 I will describe my improved track-instrument first in detail, and afterward in connection with the signal-lanterns and line and local connections.

At the inner side of the track-rail A is located a bowed flat spring, B, having its ends 35 a looped and returned parallel with the body of the spring for receiving the studs b , projecting from plates c , secured to the railway-ties. The spring B is arranged with its con-40 vex face toward the track-rail A, and to its center is secured an apertured ear, d, for receiving a bolt, e, which passes through a rod, C, extending horizontally through a hole in the track-rail and supported by a guide, D, 45 secured to the rail.

At a suitable distance from the railroad-track is secured a casing, E, having a rectangular chamber, F, with a spring-chamber, G, on one side thereof, and a larger spring-cham-50 ber, H, upon the opposite side, the chambers G H being axially in line with each other. In

the chamber G is placed a spring, f, and a rod, I, having a T-shaped head, J, located within the chamber H, extends through the walls of the chamber F and through the spring f in 55 the chamber G, and is provided with a collar, g, which bears upon the spring f and loosely fits the chamber G, the said collar being held in its place on the rod I by the nut h and the jam-nut i , received on the threaded end of the 60 rod.

On opposite sides of the chamber F, adjoining the chambers G H, are placed brackets K K', of insulating material, to which are secured the contact-springs $j j' j'' j''$, the springs 65 $j j'$ being secured to the insulating-bracket K, and the springs $j'' j''$ being secured to the bracket K'. Each contact-spring consists of a strip of metal bent at right angles, with its short arm secured to the insulating-bracket and its 70 longer arm extending downward toward the bottom of the chamber F and returned parallel with itself, with its free end slotted.

To the rod I is secured a sleeve, L, carrying an arm, M, at right angles to the rod. To the 75 upper edge of the arm M is secured a metallic bar, N, which is of sufficient length to contact with either pair of springs $j j'$ or $j'' j''$. The arm M is apertured, and slides on a guide-rod, O, extending across the chamber F.

The rod C, connected with the spring B, extends axially into the chamber H of the casing E, and is provided at its extremity with a flange, P, upon which rests one end of a spring, Q. An apertured plate, k, is placed on the 85 opposite end of the spring and connected with the T-head J of the rod I by rods $l l$, extending through the plate k, flange P of the rod C, and through the T-head J of the rod I, the said rods $l l$ being provided at their inner ends with T-shaped rods m , and at their outer ends with nuts n , which rest upon the plate k. The spring Q is sufficiently strong to move the rod I against the pressure of the spring f until the collar g strikes a sleeve, o, which limits the 90 movement of the rod I. Any further movement of the rod C in the same direction simply compresses the spring Q without otherwise affecting the circuit opener and closer. The movement of a train over the track brings 95 the flanges of the car-wheels into contact with the spring B, pushing it laterally, drawing the 100

rod C, and, through its connection with the rod I, moving the said rod, so as to break contact between the bar N and the springs $j^2 j^3$ and make contact between the said bar N and the springs $j j'$. After the passage of the train the resilience of the springs B f returns the bar N to its normal position in contact with the springs $j^2 j^3$.

The lantern R, employed for a system arranged to be worked by an open circuit, contains an arm, p, carrying at its lower end a banner, q, which, by its own gravity, hangs vertically, allowing the white light of the lamp employed in the lantern to shine through the bull's-eye r. In one side of the lantern is located an electro-magnet, S, and the armature-lever s supports an armature, t, within the field of the magnet. The armature-lever s is prolonged above the bull's-eye r and is connected by a link, u, with the arm p, so that when the circuit is open the banner q will hang normally out of the path of the light passing through the bull's-eye r; but when the circuit is closed (in the manner presently to be described) the armature t will be attracted toward the magnet S, moving the armature-lever s in the same direction and causing the banner q to pass between the lamp and the bull's-eye r, thereby showing a colored light and indicating "danger."

A lantern, R, is located at each end of the section of the track to be protected. At one end of the section is placed a battery, T, and a relay-magnet, U. At each end of the track-section is placed a circuit opener and closer, like that represented in Figs. 3, 5, and 6; but the entire mechanism of the circuit opener and closer is not shown in the diagram.

To each section there are four circuit makers and breakers and four spring track-rails, which I have numbered 1 2 3 4, according to their position in the section; and for the sake of clearness in describing the operation of the apparatus I will mark one end of the section "East" and the opposite "West." The contact-spring j^2 of instrument 1 is connected by a wire, a', with the ground-wire b'. The contact-spring j^3 is connected by a wire, c', with the front contact, d', of the relay U. The contact-springs $j j'$ in this instrument are not used. In instrument 2 the contact-springs $j^2 j^3$ are not used; but the contact-spring j is connected by a wire, e', with the ground-wire b', and the contact-spring j' is connected with the line-wire f', and the said line-wire f' is connected by a wire, g', with one terminal of the magnet of the relay U and with the armature-lever h' of the relay U. The remaining terminal of the relay U is connected with one pole of the battery T, the opposite pole being connected with one terminal of the magnet S of the lantern R, and the remaining terminal of the electro-magnet S is connected with the line-wire i', which communicates with one terminal of the electro-magnet S of the lantern at the west end of the section. The contact-

springs $j^2 j^3$ of instrument 3 are not used. The contact-spring j is connected with the line-wire f', and the contact-spring j' is connected by a wire, k', with the ground-wire l'. The contact-spring j^2 of instrument 4 is connected with the electro-magnet S of that end of the line by a wire, m', and the contact-spring j^3 connects with the ground-wire l', while the contact-springs $j j'$ are not used. When the section is occupied, the banners q at each end of the section hang vertically, and a white light is displayed through the bull's-eyes r, indicating that the track is clear; but when a train enters the section from the east, for example, the wheels of the train first engage the spring B of track-instrument 1, drawing away the bar N from the contact-springs $j^2 j^3$ without producing any effect upon the circuit; but when the wheels touch the spring B of track-instrument 2 it withdraws the bar N from the contact-springs $j^2 j^3$ and brings it into contact with the contact springs $j j'$. The current from the battery T now flows through the magnet of the relay U, through the wire g', wire f', spring j', bar N, spring j, and wire e' to the ground-wire b', and in the opposite direction from the battery through the magnet S of the lantern R at the east end of the section, through the line-wire i', magnet S of the lantern at the west end of the section, wire m', through the spring j^2 , bar N, and spring j^3 of instrument 4 to the ground-wire l'. The magnets S are energized, drawing forward the armature-levers s, thus bringing the banners q over the bull's-eyes r, indicating that the section is occupied. At the same time the armature-lever h' of the relay U makes contact with the front contact, d', of the relay, so that after the train passes instrument 2 of the section, and the circuit is broken between the springs $j j'$ of that instrument, the line finds a ground at the east end of the section through the relay U, armature-lever h', contact-point d', wire c', spring j^3 , bar N, spring j^2 , and wire a' to the ground-wire b'. When the train enters the west end of the section, the wheels of the train engage the spring B of instrument 3, withdrawing the bar N of that instrument from the springs $j^2 j^3$, bringing it into contact with the springs $j j'$, but producing no effect upon the circuit. When the train reaches instrument 4, the engagement of the wheels with the spring B withdraws the bar N from the springs $j^2 j^3$, thus breaking the circuit, releasing the armature-levers s of the lanterns, allowing them to fall, at the same time releasing the armature-lever h', allowing it to fall back and break connection with the contact-point d'. The circuit and the instrument remain in this condition until another train enters the section.

If the system is applied to a single-track road, a train entering the section from the west first operates track-instrument 4, breaking connection between the bar N and the springs $j^2 j^3$, and making connection with the springs

j, j' without producing any effect; but when instrument 3 is operated the bar N is drawn away from the springs j^2, j^3 and brought into contact with the springs j, j' . The current then 5 momentarily flows from the battery T, through the magnet S of the lantern at the east end of the section, through the line-wire i' , magnet S of the lantern at the west end of the section, through the wire m' , spring j^2 , bar N, and 10 spring j^3 of instrument 4 to the ground. The current flows in the opposite direction from the battery T, through the magnet of the relay U, through the wire g' , line-wire f' , spring j , bar N, and spring j' of instrument 3, and 15 through the wire k to the ground-wire l' , thus energizing the magnet of the relay U, bringing forward its armature-lever and establishing a contact between the lever and the contact-point d' , and when the train has left instrument 20 the current from the battery T flows through the magnet S of the lantern at the east end of the section, through the line-wire i' , magnet S of the lantern at the west end of the section, wire m' , and the spring j^2 , bar N, and 25 spring j^3 of instrument 4 to the ground-wire l' . The current flows from the battery in the opposite direction through the wire g' , armature-lever h' , contact-point d' , wire c' , and spring j^3 , bar N, spring j^2 of instrument 1, and the 30 wire a' to the ground-wire b' . The magnets S of the lanterns at opposite ends of the sections being energized, their armature-levers s are drawn forward, and the banners q are held between the bull's-eyes r and the source of light, 35 thus indicating that the section is occupied. In passing off the section the engagement of the car-wheels with instrument 2 produces no effect; but in passing instrument 1 the bar N is withdrawn from the springs j^2, j^3 , breaking the 40 circuit, allowing the armature-levers of the lantern-magnets and of the relay-magnet to return to their normal position, leaving the circuit open and indicating "safety" at the lanterns by again displaying a white light.

45 In the system shown in Fig. 2, in which the banners are held to a position of "safety" by the action of the current and the danger-signal is displayed by interrupting the circuit, the conditions are reversed and the electrical connections are slightly varied; but the general construction and arrangement of the system remain the same. Therefore a description of the operation of the closed-circuit system will 50 make clear the difference between its construction and that of the open-circuit system shown in Fig. 1. The same letters of reference will indicate the same parts.

When the section is unoccupied, the current flows from the battery T, through the magnet 55 S of the lantern at the east end of the section, through the line-wire i' , through the magnet S at the west end of the section, through the wire m' , spring j^2 , bar N, spring j^3 of instrument 3, thence through the wire k to the ground-wire l' . The current flows from the battery T in the opposite direction through the

spring j^2 , bar N, spring j^3 of instrument 2, magnet of the relay U, armature-lever h' , front contact, d' , and wire c' to the ground-wire b' . The armature-lever h' of the relay is held forward in contact with the point d' , and the armature-levers s of the lanterns R are drawn forward toward their magnets, so as to hold their banners q in the position of "safety." A train entering the section from the east engages track-instrument 1 without producing any effect; but when track-instrument 2 is operated the bar N is drawn away from the springs j^2, j^3 , thus breaking the circuit, allowing the armature-lever h' to fall back and break contact with the contact-point d' , and the armature-levers s , being released, permit the banners q to drop over the bull's-eyes r and indicate "danger."

When the train reaches the west end of the section, it engages track-instrument 3 without producing any effect other than opening the already-opened circuit between the springs j^2, j^3 ; but when the train passes instrument 3 the bar N regains its position in contact with the springs j^2, j^3 . When track-instrument 4 is engaged by the train, the bar N is brought into contact with the springs j, j' of instrument 4, thus momentarily completing the circuit. The current then flows from the battery T in one direction through the magnet S of the lantern at the east end of the section to the line-wire i' , through the magnet S at the west end of the section, wire m' , spring j^2 , bar N, spring j^3 , through the wire k to the ground-wire l' , and 100 in the opposite direction from the battery T through the spring j^2 , bar N, spring j^3 of instrument 2, magnet of the relay U, wire g' , line-wire f' , spring j , bar N, and spring j' of instrument 4 to the ground-wire l' . The magnet of the relay is thus temporarily magnetized by the current flowing in the direction just described, and the armature-lever h' is drawn forward, making contact with the contact-point d' , when the current flows from the 105 battery T in one direction through the magnets S of the lanterns and the line-wire i' , the wire m' , spring j^2 , bar N, spring j^3 of instrument 3, and wire k to the ground-wire l' , and in the opposite direction through instrument 110 2, magnet of the relay U, armature-lever h' , contact-point d' , and wire c' to the ground-wire b' . The magnets S, being energized, hold the banners q in the position of safety so long as the section is unoccupied.

The train from the west engages instrument 4 without producing any effect, but on reaching instrument 3 breaks the circuit between the springs j^2, j^3 , so that no current flows over the line, thus releasing the armatures of the lanterns and of the relay and breaking the circuit between the armature-lever h' and the contact-point d' . The passage of the train over instrument 2 produces no effect other than momentarily breaking connection between springs j^2, j^3 . The circuit remains open until the train engages track-instrument 1,

when the contact of the bar N with the springs j, j' closes the circuit and causes the armature-lever h' of the relay U to complete the circuit through the contact-point d' , thus holding the circuit closed and causing the banners g to be held to the position of safety so long as the track-section is unoccupied.

Having thus fully described my invention, I claim as new and desire to secure by Letters

to Patent—

1. In railway signaling apparatus, the combination of two track-instruments located near opposite ends of the section to be protected and constructed to hold the circuit normally open, two track-instruments located near opposite ends of the section and arranged to hold the circuit normally closed, two electro-magnetic signals located at opposite ends of the section, a single relay adapted to hold the circuit open or closed during the occupation of the section, an electric generator connected with one track-instrument at each end of the section and with the conductor, including the

signal-magnets, and the line and local connections, substantially as specified.

2. The combination, in a track-instrument for railway signaling apparatus, of a casing, E, provided with a chamber, F, and contact-springs j, j', j^2, j^3 , the rod I, contact-bar N, carried by the rod I, the spring f, the stop o, the auxiliary spring Q, the rod C, provided with the head P, the plate k, and the rods l, substantially as specified.

3. The combination, in a track-instrument for railway signaling apparatus, of a casing, E, provided with a chamber, F, and contact-springs j, j', j^2, j^3 , the rod I, contact-bar N, carried by the rod I, the spring f, the stop o, the auxiliary spring Q, the rod C, provided with the head P, the plate k, the rods l, the spring B, connected with the rod C, and the guiding-studs b, substantially as specified.
